ELECTRIC CAN OPENER

George Rico Drugman, West Palm Beach, Fla.

Application October 22, 1947, Serial No. 781,273

2 Claims. (Cl. 30—4)

1

This invention relates to an electric can opener.

It is an object of the present invention to provide an electric can opener having an electric motor carried on a vertical support and from which there is extended a bracket adapted to support a can to be opened and wherein on the same bracket there is a knife adapted to be brought down into the top of the can to open the can as the motor is started to drive a wheel engaging with the can to rotate the same, and wherein the operation of the motor is effected automatically as the knife is brought down into the can by virtue of a contact being closed as the knife is driven home into the can.

Other objects of the present invention are to provide an electric can opener which is of simple construction, inexpensive to manufacture and efficient in operation.

For a better understanding of the invention, reference may be had to the following detailed description taken in connection with the accompanying drawing, in which

Fig. 1 is a side elevational view of the electric can opener embodying the features of the present invention with the can in place on the support and the cutting blade raised above it,

Fig. 2 is a top plan view of the can opener,

Fig. 3 is a front elevational view of the can opener,

Fig. 4 is an enlarged longitudinal sectional view of the can opener with the blade extended into the can, the view being taken on line 4—4 of Fig. 2,

Fig. 5 is a detail sectional view taken on line 5—5 of Fig. 4,

Fig. 6 is a wiring diagram including the motor and the switch for starting the operation of the motor.

Referring now to the figures, 10 represents the base from which there extends upwardly a vertical support 11. On the upper end of this vertical support there is connected an operating motor 12. Extending from the end of this operating motor is a bracket construction 13 for supporting the operating parts and the can to be opened. This bracket is fully contained upon the motor and is supported upon the base only through the motor and the upright support 11 thereof. This bracket 13 comprises a plate 15 which is secured on four extensions 16 extending outwardly from the motor housing. The plate 15 is retained on the extensions by fastening nuts 17. In the plate 15 is a bearing sleeve 18 through which extends an operating shaft 19

2

having a worm pinion 21 on its outer end. Extending forwardly from the plate 15 are two extensions 22 and 23, vertically spaced from one another for supporting a shaft 24 having a worm wheel 25 adapted to be driven by the worm 21. This worm wheel is adapted to engage the side of a can 26 to rotate the same. The can is supported on a turn table 27 pivotally connected with the horizontally extending portion 28 of

10 an adjustable can support 29 of a depending sleeve 30 extending from plate 15. The support 29 is adjustably connected to the sleeve 30 and is retained in any one of its adjusted positions by a set screw 31.

15 In order to retain the can 26 on the turn table 27 against lateral displacement there is an adjustable ring strap 32.

On the extensions 23 is a plate 34 having a hole in its outer end to which a cutting blade or 20 knife 35 is extended and guided when thrust into the can top. The plate 34 has upwardly extending ears 36 between which is pivoted an operating arm 37 having a handle 38 thereon. The blade 35 has a member 39 extending from 25 the top thereof to the lugs 36 wherein it is guided by a pin 41 working in an elongated slot 42. A projection 43 on the arm 37 will engage the member 39 to operate push button 44 to which wires 45 extend. This push button when moved 30 to a closed position will close the motor circuit to cause the rotation of the motor and the rotation of the can. Thus automatically as the cutting blade is extended into the can top by the lever or operating member 37 the motor will be started. At the end of the cutting operation, the operating member 37 is raised and compression springs 47 acting between the member 39 and the plate 34 will raise the cutting knife 35.

Having now described my invention, I claim:

40 1. An electric can opener comprising a base, an upright support extending upwardly from the base, an electric motor secured to the upper end of the upright support, a shaft extending from the motor and having a pinion thereon, a bracket construction secured to the housing of the electric motor and on the end thereof from which the pinion shaft extends, said bracket construction including a vertically-extending plate, a sleeve depending from the plate and said bracket construction having two parallel vertically spaced extensions supporting a wheel adapted to be rotated by the pinion, a support on the bracket construction, said support being adjustable in the sleeve, and means for retaining 45 the support in any of its adjusted positions

50 55

therein, a turn table on the support adapted to receive the can, a knife movable on the bracket construction for insertion within the top of the can while the can is in position on the turn table to be rotated, a manually operable means for causing the downward thrust of the knife into the can, an extension on the bracket construction for the knife, said extension having an electric switch thereon, a member extending from the blade and adapted to operate the switch to start the motor automatically as the knife is urged into the can, an operating lever adapted to engage said member to operate the knife, and biasing means for returning the member and the knife when the operating lever is removed from its engagement with the member on the knife.

2. An electric can opener as defined in claim 1 and an adjustable ring extending outwardly

from the sleeve and adapted to surround the can whereby to retain the can in place on the turn table as the can and turn table are rotated.

GEORGE RICO DRUGMAN.
